UNITED STATES PATENT OFFICE.

MAX RUBIN, OF NEW YORK, N. Y.

DESIGN FOR A BASE FOR CALENDARS.

SPECIFICATION forming part of Design No. 29,665, dated November 15, 1898.

Application filed August 8, 1898. Serial No. 688,116. Term of patent 7 years.

To all whom it may concern:

Be it known that I, MAX RUBIN, a citizen of the United States, residing at the city of New York, borough of Manhattan, in the county 5 of New York and State of New York, have invented and produced a new and original Design for the Base of a Calendar, of which the following is a specification, reference being had to the accompanying drawing, forming a 10 part thereof, which represents in face view the base of a calendar embodying my new design.

The leading feature of my design for the base of a calendar consists in the unitary article made the subject of this illustration and 15 description.

Upon the base A, I produce the representation B of the body of a flag and at one side thereof the representation of a staff C.

D are slots which extend transversely the length of the representation of the body of 20 the flag and are spaced apart a distance corresponding to the size of the field of the flag.

I claim—

The design for the base of a calendar herein shown and described.

MAX RUBIN.
